(57) **CLAIM**

The ornamental design for a protective sleeve for a container, as shown.

DESCRIPTION

FIG. 1 is a front perspective view from above of one embodiment of a protective sleeve;

FIG. 2 is a front perspective view from below of FIG. 1;

FIG. 3 is a front view of FIG. 1;

FIG. 4 is a rear view of FIG. 1;

FIG. 5 is a top view of FIG. 1;

FIG. 6 is a bottom view of FIG. 1;

FIG. 7 is a front perspective view from above of a second embodiment of a protective sleeve;

FIG. 8 is a front perspective view from below of FIG. 7;

FIG. 9 is a front view of FIG. 7;

FIG. 10 is a rear view of FIG. 7;

FIG. 11 is a top view of FIGS. 7; and,

FIG. 12 is a bottom view of FIG. 7.

The broken lines “Logo Here” in FIGS. 7, 8, and 9 are for illustrative purposes only and form no part of the claimed design.
